(57) **CLAIM**

The ornamental design for capsules for mixing multiple substances, as shown and described.

DESCRIPTION

FIG. 1 is a perspective view of a first embodiment of capsules for mixing multiple substances, showing our new design;

FIG. 2 is a top view thereof, the bottom view being a mirror image;

FIG. 3 is a left side view thereof, the right side view being a mirror image;

FIG. 4 is a front view thereof;

FIG. 5 is a rear view thereof;

FIG. 6 is a perspective view of a second embodiment of capsules for mixing multiple substances, showing our new design;

FIG. 7 is a top view thereof, the bottom view being a mirror image;

FIG. 8 is a front view thereof;

FIG. 9 is a left side view thereof, the right side view being a mirror image; and,

FIG. 10 is a rear view thereof.

Broken lines in the drawings denote features of the article that are included for the purpose of illustrating context, but form no part of the claimed design.

The separations depicted by the break lines are the bounds of the claim and any portion between the break lines forms no part of the claimed design.
